(57) **CLAIM**

The ornamental design for a guitar body, as shown.

DESCRIPTION

FIG. 1 is a front view of the guitar body;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a top, left, front perspective thereof with the environment removed for clarity of disclosure; and,
FIG. 8 is a top, left, front perspective thereof within an environment.
In the drawings, the broken lines showing portions of the guitar depict environment and form no part of the claim.
